UNITED STATES PATENT OFFICE

2,610,860

AUTOMATIC CHUCK

Richard L. Coan, Cleveland, Ohio, assignor to
United States Steel Company, a corporation of
New Jersey

Application June 13, 1950, Serial No. 167,859

3 Claims. (Cl. 279—119)

1

The present invention refers to a chuck and more particularly to an automatic chuck mechanism especially suitable for use on die sizing machines.

It is an object of my invention to provide an automatic chuck mechanism which may be actuated by a single lever to either grip a workpiece within its jaws or eject the workpiece after work has been performed thereon.

The invention will be fully apparent from the following detailed disclosure and the appended claims when read in connection with the accompanying drawings, in which:

Figure 1 is a top plan view of my device;

Figure 2 is a side elevation, partly in section, 15 of Figure 1;

Figure 3 is a sectional view taken on the line III—III of Figure 1, showing the chuck in gripping position; and

Figure 4 is a view similar to Figure 3 showing 20 the chuck in expanded position.

Referring more particularly to the drawings, the reference numeral 2 indicates the base of a lapping machine of the type shown in the patent to Kutzler, No. 2,391,983, dated January 1, 1946. Base 2 has an upwardly extending bearing support 4 which receives the ball bearings 6. Chuck body 8 is rotatably mounted in the bearings 6 and has a sheave 10 attached to the lower part thereof which is rotated by means of belt 12. The chuck body 8 has an axial opening 14 therethrough for receiving a hollow sleeve 16 which has a shoulder 18 at its upper end. Slidably received in the opening in the sleeve 16 is a spindle 20 having its upper end attached to a pad 22. The spindle 20 passes downwardly through the base 2 and a bearing 24 with its lower end being threaded into a cap 26. A cup member 28 is threaded to the outside of cap 26. Locking nuts 30 and 32 are provided for locking the cap 26 and cup member 28 in position. A spring 34 surrounds the cap 26 and spindle 20 with one end bearing against the bearing 24 and the other end being received in the cup member 28. The lower end of the cap 26 is bifurcated at 36. An operating lever 38 is pivotally mounted intermediate its ends on a pin 40 which is supported on a bracket 42 attached to the machine frame. One end of lever 38 extends between the bifurcations 36 and is pivotally connected to cap 26 by means of a pin 44 which is supported in the bifurcations 36 and passes through an elongated hole 46 in the end of lever 38. The other end of lever 38 extends into position to be operated by the operator or, if desired, suitable power means may be provided.

A spring 48 surrounds the sleeve 16 with its lower end resting on a shoulder 50 in the chuck body and its upper end bearing against a washer 52. A bearing 54 also surrounds the sleeve 16

2

above the washer 52. The washer 52 and bearing 54 are held in spaced apart relationship by means of three bell-crank levers 56 which are pivotally mounted in openings 58 in the chuck body. Upward movement of bearing 54 is limited by a shoulder 59 in the chuck body 8. As best shown in Figures 3 and 4, each of the levers 56 has a substantially horizontal arm 60 which extends between the washer 52 and bearing 54. The other arm 62 of each of the levers 56 extends upwardly into an opening 64 formed in the lower half 66 of an adjustable jaw which is slideable in radial slots 68 in the chuck housing. The upper half 70 of each jaw is provided with an elongated opening 72 so that it can be adjusted radially with respect to the lower portion 66 and clamped in adjusted position by means of a cap screw 14.

The operation of the device is as follows:

The pad 22 is raised by applying pressure to the outer end of the lever 38, this pressure compressing the spring 34. At the same time, spring 48 expands, thus rotating bell-crank levers 56 counterclockwise about their axes to move the jaws 66 radially outward. The die D to be lapped is then placed on the pad 22 by feed mechanism (not shown) or manually with the pad 22 in its raised position as shown in Figure 4. Pressure on the outer end of lever 38 is then released, enabling the spring 34 to move the spindle 20 and pad 22 downwardly to the position shown in Figure 3. This downward movement causes the shoulder 18 on the sleeve 16 to force the bearing 54 and the arms 60 of levers 56 downwardly against the pressure of the spring 48, thus compressing the spring 48. Downward movement of the arms 60 also causes the levers 56 to pivot about their axes, thus moving the jaws 66 inwardly with the upper portion 70 thereof firmly gripping the die D.

After the lapping operation is completed, pressure is again applied to the outer end of lever 38 to move the pad 22 upwardly, thus permitting the spring 48 to move the jaws 66 radially outwardly. As upward movement of the pad 22 continues, the die D is ejected from the chuck which is then ready to receive another die.

While one embodiment of my invention has been shown and described, it will be apparent that other adaptations and modifications may be made without departing from the scope of the following claims.

I claim:

1. An automatic chuck comprising a chuck body having an axial bore therein, a pad disposed for axial movement within said axial bore, a plurality of jaws mounted for radial movement on said chuck body around said pad, a spindle attached to and extending downwardly from said pad through said bore, an elongated bushing sur-

rounding the upper portion of said spindle, actuating means for said jaws, a spring surrounding said bushing beneath said pad and bearing against said actuating means to urge said jaws outwardly away from said pad, lowering of said spindle moving said jaws inwardly against the action of said spring means, and operating means for raising and lowering said spindle.

2. An automatic chuck comprising a chuck body having an axial bore therein, a pad disposed for axial movement within said axial bore, a plurality of jaws mounted for radial movement on said chuck body around said pad, a plurality of bell cranks pivoted in said chuck body one beneath each of said jaws, each of said bell cranks having a pair of arms, one arm of each bell crank being connected to its associated jaw, the other arm of each of said bell cranks extending inwardly, a spindle attached to said pad and extending downwardly through said bore, a bushing surrounding the upper portion of said spindle beneath said pad, a bearing surrounding said bushing above said inwardly extending bell crank arms, a spring surrounding said bushing beneath said inwardly extending bell crank arms and bearing thereagainst to urge said jaws outwardly away from said pad, lowering of said spindle moving said jaws inwardly against the action of said spring, and operating means for raising and lowering said spindle.

3. An automatic chuck comprising a chuck body having an axial bore therein, a pad disposed for axial movement within said axial bore, a plurality of jaws mounted for radial movement on

said chuck body around said pad, a plurality of bell cranks pivoted in said chuck body one beneath each of said jaws, each of said bell cranks having a pair of arms, one arm of each bell crank being connected to its associated jaw, the other arm of each of said bell cranks extending inwardly, a spindle attached to said pad and extending downwardly through said bore, a sleeve surrounding the upper portion of said spindle beneath said pad, a bearing surrounding said bushing above said inwardly extending bell crank arms, a washer surrounding said spindle below the inwardly extending bell crank arms, a spring surrounding said bushing beneath said washer with one end bearing against said chuck body and the other end bearing against said bell crank arms to urge said jaws outwardly away from said pad, an abutment on said chuck body above said bearing for limiting upward movement thereof, lowering of said spindle moving said jaws inwardly against the action of said spring, and operating means for raising and lowering said spindle.

RICHARD L. COAN.
